UNITED STATES PATENT OFFICE.

WILLIAM E. FOWLER, SR., OF CHICAGO, ILLINOIS, ASSIGNOR TO THE FOWLER CAR COMPANY, OF CHICAGO, ILLINOIS, A CORPORATION OF ILLINOIS.

TIGHTENER FOR CAR SIDES.

1,079,331.

Specification of Letters Patent.

Patented Nov. 25, 1913.

Application filed September 23, 1912. Serial No. 721,877.

To all whom it may concern:

Be it known that I, WILLIAM E. FOWLER, Sr., a citizen of the United States, residing at Chicago, in the county of Cook and State 5 of Illinois, have invented certain new and useful Improvements in Tighteners for Car Sides, of which the following is a specification.

My invention relates to railway cars and 10 has particular reference to means for tightening the sides and ends of single sheathed box cars such as shown in my earlier Patent No. 962,425. In the operation of such single sheathed cars it has been found necessary 15 to provide some means for taking up shrinkage or warping in order that such cars shall be adapted for the transportation of grain and similar material. Means for securing this tightening effect are shown in my earlier 20 patent before mentioned, the tightening straps being located on the interior of the car. This is objectionable to some railroads in that a plane surface is not possible for the car interior; an objection is made also 25 to the location of the tightening nut at the end of the strap. With the strap located on the interior of the car the lower end must be located behind the side sill in an inaccessible 30 position. Furthermore the side sill must be weakened by removing portions of the metal to provide an aperture for the end of the strap.

This invention has for a principal object 35 the provision of tightening rods on the exterior of the car side, together with easily accessible means for tightening the sides, all without weakening the side sill or any of the car frame.

In view of the objections to the heretofore known tightening means many cars 40 have been sent out without any means for taking up shrinkage. The construction described herein is particularly adapted for application to such cars without dismantling 45 or disturbing the sides, other than the top board.

The invention will be more readily understood by reference to the accompanying 50 drawings, wherein—

Figure 1 is a fragmentary side elevation of a single sheathed car showing my invention applied thereto; Fig. 2 is a transverse vertical section on the line 2—2 of Fig. 1; Fig. 3 is an enlarged sectional detail of the 5 upper end construction; Fig. 4 is a detail

of a slight modification of the lower end construction, taken on the line 4—4 of Fig. 1; and, Fig. 5 is a section taken on the line 5—5 of Fig. 1.

Referring more particularly to the drawings it will be seen that the car of my invention is composed of the usual elements including a channel side sill 10, Z-bar top sill 11, corner angles 12, Z-bar vertical posts 13 and diagonals 14. An angle 15 adjoins the corner angle 12, the two angles forming the support for the ladder rungs. It will be seen that the car side is composed of a single thickness of boards 16, placed edge to edge; also that the angular frame members of the car are slotted, bolts 17 forming the 70 securing means for the sides.

The tightening means of my invention comprise a rod 18, having a broad flat, hooked upper end 19. This is hooked over the top board and may if desired be secured to such board by means of a lag bolt 20. In order to avoid any interference with the side frame members, the rods are located, as shown, underneath the outstanding leg 13¹ 80 of the vertical Z-bars, and, if a tightening rod is required at the end of the car, such rod is located alongside the ladder angle. It will be seen that the rods may be located at any of the points shown without slotting 85 the diagonals or interfering with the corner gussets. This is important both in the interest of economy and in the adaptability of the means for cars already in service.

I have shown two forms of abutments 90 against which the tightening nut may seat at the lower end of the rod, both providing for ready accessibility. The form shown specifically in Fig. 2 and at the left-hand side of Fig. 1 comprises merely a hooked forging 95 21, the hood engaging the lower flange of the channel side sill 10. The forging is properly apertured, the rod lying against the web of the channel; by thus placing the rod, the nut may exert a portion of its force in 100 line with the channel instead of applying a bending force to the overhung end of the forging or casting 21. If desired, the overhung end of the part 21 may project out beneath and having a bearing on the leg 13¹ 105 of the side stake 13. Thus the forging is supported at both ends.

It may be desirable in applying the tightening means to cars in course of construction to employ the form shown in Figs. 4 and 5 110

2

and at the center of Fig. 1. In this I contemplate bridging the space between the webs of the vertical and diagonal Z-bars 13 and 14 by means of a plate 22 suitably riveted or otherwise secured. This plate being apertured the rod may extend therethrough, the plate providing an excellent abutment for the nut. This form may be easily applied to cars already in service, without riveting or bolting by merely bridging the space between the two webs with a flat plate. Even assuming the loosening of the nut, the rod cannot swing outward or escape, it being seated behind the leg 13¹ of the Z-bar.

15 It will be understood that while I have shown the tightening means as applied to a car having Z-bar exterior framing, it is equally adaptable to cars having framing composed of other commercial shapes, the 20 gist of the invention being the application of exterior tightening means, the tightening nut being readily accessible as required. It will be understood also that while I have described and shown the improvement as applied to the side walls of a car, it may be 25 equally well applied to the end walls thereof.

I claim:

1. In a car having exterior framing and

an inner wall, the combination of tightening means secured over the top of the wall 30 and passing down over the outer surface of the wall, and an abutment located exteriorly of the car wall for a tightening nut, the arrangement being such that the nut is exposed to the exterior of the car, substantially 35 as described.

2. In a car, the combination of side walls and an exterior framing, of a tightening rod hooked over the upper edge of a wall, an abutment projecting outwardly from the car 40 side sill and providing a bearing for a tightening nut exteriorly of the car wall, substantially as described.

3. In a car, the combination of side walls and an exterior framing, of a tightening rod 45 hooked over the upper edge of a wall, an abutment hooked to the car side sill and projecting outwardly therefrom, thereby providing a bearing exteriorly of the car wall for a tightening nut on said rod, substantially 50 as described.

WILLIAM E. FOWLER, SR.
